UNITED STATES PATENT OFFICE.

SPENCER OTIS, OF CHICAGO, ILLINOIS, ASSIGNOR TO NATIONAL DUMP CAR COMPANY, A CORPORATION OF MAINE.

FREIGHT-CAR.

No. 902,678.

Specification of Letters Patent.

Patented Nov. 3, 1908.

Application filed April 15, 1907. Serial No. 368,415.

To all whom it may concern:

Be it known that I, SPENCER OTIS, a citizen of the United States, residing at Chicago, in the county of Cook and State of Illinois, have invented certain new and useful Improvements in Freight-Cars, of which the following is a specification.

My invention relates in general to railroad freight cars, and more particularly to a combined box and dump car.

Freight cars used to haul in one direction freight for which a box car is best adapted must frequently on the return trip haul material for which a dump car is most suitable. It is therefore desirable that freight cars should be capable of use either as box cars or dump cars.

One of the objects of my invention is to provide a freight car which may be used either as a box car or as a dump car, as occasion may require, and which when used in either capacity may be easily loaded and unloaded.

A further object of my invention is to provide a freight car which will have the requisite structural strength to sustain a maximum load without the employment of the usual tension rods extending beneath the longitudinal car sills.

A further object of my invention is to provide an improved dump car, which will be simple in construction, strong and durable in use, and efficient in operation.

The embodiment of my invention herein disclosed may be generally described as consisting of a freight car, comprising tension members on the opposite sides of the car secured to the side sills intermediate of their ends and extending upwardly to the upright posts at the ends of the car to which they are secured, sliding side doors having hinged sections, the lower sections adapted to swing outwardly, sliding doors on the car roof on opposite sides of the longitudinal center through which material may be loaded, transverse braces beneath the roof intermediate of the door openings, downwardly swinging doors in the bottom of the car on the opposite sides thereof, longitudinal shafts beneath the opposite sides of the car having pinions thereon engaging rack bars secured to the under sides of the doors, upwardly inclined guides with which the shafts engage and by which they are directed upwardly when rotated, thereby closing the bottom doors, and means for rotating the shafts.

My invention will be more fully disclosed hereinafter with reference to the accompanying drawings, in which the same is illustrated as embodied in a convenient and practical form, and in which—

Figure 1 is a side elevational view, the left portion of the car being broken away; Fig. 2, an enlarged detail perspective view, showing the connection of one end of a tension member with the car; Fig. 3, a detail perspective view of one of the bottom plates to which the tension members are secured; Fig. 4, a sectional view on line 4, 4, Fig. 3; Fig. 5, a plan view of the top of the car, the left portion thereof being broken away; Fig. 6, an enlarged sectional view on line 6, 6, Fig. 5; Fig. 7, a sectional view on the line 7, 7, Fig. 6; Fig. 8, a sectional view on the line 8, 8, Fig. 6; Fig. 9, an enlarged sectional view on line 9, 9, Fig. 5; Fig. 10, an end elevational view, showing the shaft rotating means; Fig. 11, a sectional view on line 11, 11, Fig. 1, showing the bottom door closed; Fig. 12, a view similar to Fig. 11, showing the door open; Fig. 13, a view similar to Fig. 12, showing a modification; and Fig. 14, an enlarged detail sectional view on line 14, 14, Fig. 1.

Similar reference characters are used to designate similar parts in the several figures of the drawings.

Reference letter A indicates one of the longitudinal side sills of a freight car, which is shown as made of an angle bar.

B designates one of the upright posts at one end of the car upon the upper end of which is supported one end of the roof beam C.

D indicates one of the corner braces, which unites one end of one of the side sills to the lower end of the corresponding upright post.

E designates a corner brace for rigidly uniting the upright post B to the overlying roof beam C.

B' indicates a second upright intermediate of the side sill and roof beam, the lower end of which is rigidly secured to the side sill by the brace plate D', while its upper end is rigidly secured to the roof beam by the brace plate E'.

B² designates a third upright post secured at its lower end by a brace plate D² to the side sill and at its upper end by a brace plate E² to the roof beam. In order to impart greater rigidity to the car structure, diagonal

braces b' , b^2 are interposed between the upright posts and are rigidly secured to the corresponding brace plates E' , D' and E^2 .

F designates a plate rigidly secured to the side sill A intermediate of its ends and provided with an inwardly extending flange f overlying the top of the side sill. Rigidly secured to the side portions f' and f^2 of the plate F are the lower ends of tension members F' , F^2 , respectively. Each of these tension members extends upwardly and is secured at its upper end to the corresponding brace plate E in any suitable manner, as by means of a tubular socket e on the brace plate through which the end of the tension member extends, a nut being secured to the end of the tension member projecting through the socket. The tension member extends over a guide e' upon the brace plate E' . In order to remove the slack from the tension members turn-buckles are provided.

G designates the roof of the car which is provided with the usual longitudinal platform g at the center thereof upon which the trainmen walk. Openings are provided through the roof on opposite sides of the longitudinal center, such openings being controlled by sliding doors G' and G^2 . Each of the sliding doors is provided with inwardly extending flanges g' and g^2 beneath the edges thereof, which engage longitudinal guides H' and H^2 secured to the car roof along the edges of the openings. In order to guide the roof doors during their opening and closing movements short guides h' and h^2 are secured to the car roof in alinement with the guides H' and H^2 . Stops h are provided for limiting the closing movement of the doors.

In order that the car roof may be strengthened to compensate for the weakening effect of the door openings therethrough, a transverse brace K is provided intermediate of each pair of door openings. Such braces may be conveniently secured beneath the car roof by end projections k' and k^2 which are supported within hangers L' and L^2 , depending from the central door guides H' , H^2 . The central door guides are, preferably, made of angle bars to which the hangers are secured by angle brackets l' and l^2 . The usual transverse roof beams K' and K^2 are provided on opposite sides of the door openings.

Located beneath the bottom of the car are longitudinal shafts M' and M^2 , such shafts being located in alinement, and a pair of such aligned shafts being supported beneath the opposite sides of the car and adapted to control the opening and closing of downwardly swinging floor doors N' , N^2 and N^3 , etc. In the car illustrating my invention twelve floor doors are provided, three controlled by each section of the rotating shafts, but it will, of course, be understood that a greater or less number of such doors may be provided as desired. Each of the four shafts are the same

in construction and in operation, and hence a description of one of them will be sufficient to disclose the construction and operation of all of them. The shaft M' is provided with three pairs of pinions m' , m^2 and m^3 , a pair of such pinions being located beneath each of the doors. Each door is provided with a pair of rack bars, the teeth of which mesh with the corresponding pair of pinions. In Figs. 11 and 12, n^2 indicates one of the rack bars beneath the door N^2 with which the pinion m^2 meshes. The floor doors are hinged at their inner edges in any suitable manner, as by means of strap hinges n , located beneath the rigid longitudinal center N of the car floor.

Guides are rigidly secured beneath the car for controlling the path of movement of the shafts, such guides being indicated by reference characters P' , P^2 and P^3 . These guides are located intermediate of the doors, so as not to interfere with the movement of the doors to open position, shown in Fig. 12. The upper ends of the guides are rigidly secured to the outer ends of transverse bars A^4 , while their lower ends are rigidly secured to braces a^4 , depending from the bars A^4 . The lower ends of the braces a^4 are rigidly connected by transverse braces a^3 to the bottom of the usual car center sill A^3 .

In order that the shafts may be rotated, the outer end of each one is provided with a ratchet wheel m' with which a pawl o' engages, such pawl being mounted upon a lever O' mounted to oscillate with respect to the shaft. In order that the shaft may be retained in the position to which it may be rotated, while lever O' is being returned to its initial position, a pawl O is loosely carried upon the shaft, which engages the teeth upon a ratchet P , such ratchet bar being secured to and depending from the transverse end sill A' of the car.

R designates a side door for the car which is suspended in the usual manner by means of hangers s from a track S . The lower section R' of the door is connected by hinges r' to the upper section so as to swing outwardly. A suitable fastening device, such as a bolt R^2 , is provided upon the bottom of the lower door section for retaining the door in its closed position.

r^2 designates a keeper for the bolt R^2 , such keeper being conveniently secured to the plate F . Suitable fastening devices are provided for preventing the upper section of the door from swinging outwardly, such fastening devices, being shown as hasps r , r , projecting laterally and engaging staples secured to the door jambs.

a^3 , a^3 designate transverse tension rods extending beneath the longitudinal center sill A^3 and secured at their ends to the side sills. The tension rod beneath the center of the car may be conveniently secured to the side sills

by extending its ends through bosses f^3 on the side plates F, as shown in Fig. 3.

The manner of use and operation of my improved freight car are as follows: When the car is loaded with granular or coarse material, it may be readily unloaded by detaching the bolt R² from its keeper r², whereupon the pressure of the material against the lower section R of the side door will force the same outwardly and permit the material to be discharged from the car. After the discharge of a sufficient quantity of material the entire door may be opened by sliding the same along the guide S. The material may be readily loaded into the car, either through the side doors or through the doors in the car roof, according to the character of the freight.

When the car is used for transporting material which it is desired to dump, the doors in the floor of the car are permitted to open by rotating the shafts sufficiently to disengage them from the offset seats at the upper ends of the guides, as indicated at p² in Figs. 11 and 12, when the weight of the material will effect the complete downward opening of the doors. When the load has been dumped from the car, the floor doors may be closed by oscillating the levers O' upon the ends of the respective shafts. Each oscillation of a lever O' partially rotates the corresponding shafts and elevates the same through the engagement of the pinions thereon with the rack bars beneath the corresponding doors, the shaft being directed upwardly through engagement with the corresponding guides, as indicated at P² in Figs. 11 and 12. After an oscillation of the lever O' the corresponding shaft is held in the position to which it has been raised by means of the pawl O engaging a tooth in the ratchet bar P. The lever O' is then oscillated to its initial position, so that the pawl o', through engagement with another tooth on the ratchet wheel n', will again rotate the shaft when the lever is again oscillated. In this manner each shaft is elevated until it engages within the corresponding seats at the upper ends of the guides, thereby retaining the doors controlled by such guides in closed position.

From the foregoing description, it will be observed that I have invented an improved freight car which possesses great structural strength without the use of tension rods beneath the same, tension members being provided intermediate of the side sills and the upright posts, the tendency of the car to sag when loaded being thereby resisted through the trussed structure formed by the tension members, the upright posts, the side sills, and the roof beam.

It will be further observed that I have provided an improved freight car which may be used either as a box car or freight car, and

when used in either capacity may be readily loaded and unloaded.

Having now fully described my invention, what I claim as new, and desire to secure by Letters Patent, is—

1. In a car provided with a side door opening, a side sill and a roof beam extending throughout the length of the car, upright posts at and intermediate the ends of the car and extending between the side sill and roof beam, diagonal braces extending from the lower corners of the door opening to the tops of the adjacent upright posts, and a tension member comprising two rods each secured to one end of the roof beam and to the side sill adjacent the door opening.

2. In a car, a roof beam, a side sill, tie rods, each secured at one end to one end of the roof beam and at the other end to the side sill, the points of connection between the tie rods and side sill being spaced apart whereby a truss is formed having as its compression member the roof beam, and as its tension member said tie rods and the intermediate portion of the side sill.

3. In a freight car, the combination with the side sills thereof, of upright posts at the ends of the side sills, plates rigidly secured to the side sills intermediate of their ends, and tension members extending in opposite directions from the ends of said plates to the upright posts.

4. In a freight car, the combination with the side sills thereof, of upright posts at the ends of the side sills, roof beams supported by the upright posts, corner brackets rigidly connecting the roof beam to the upright posts, and tension members on the opposite sides of the car connected at their ends to said corner brackets and to the side sills intermediate of their ends.

5. In a freight car, the combination with the side sills thereof, of upright posts at the ends of the side sills, roof beams supported by the upright posts, corner brackets rigidly connecting the roof beam to the posts, tension members on the opposite sides of the car connected at their ends to said corner brackets and to the side sills intermediate of their ends, and posts interposed between the side sills and roof beams spaced apart from the ends of the car upon which the tension members are guided.

6. In a freight car, the combination with the side sills thereof, of posts at the ends of the side sills, plates rigidly secured to the side sills intermediate of their ends, tension members extending in opposite directions from the opposite ends of said plates to said posts, corner brackets rigidly connecting the posts with the roof beam, the ends of the tension members being secured to such brackets, posts interposed between the side sills and roof beam spaced apart from the ends of the car, braces securing said latter posts to

the roof beam, and guides upon said latter braces for the tension members.

7. In a freight car, the combination with a downwardly swinging door in the floor in the bottom of the car, of a longitudinal shaft, means for rotating said shaft, a pinion fixed upon said shaft, a rack bar fixed upon the under surface of said door with which said pinion meshes, and guides secured beneath the car for supporting said shaft and directing the same upwardly when rotated to close said door.

8. In a freight car, the combination with a plurality of downwardly swinging doors in the bottom of the car, of a longitudinal shaft, means for rotating said shaft, a pair of pinions fixed upon said shaft beneath each door, a pair of rack bars fixed upon the under surface of each door meshing with the corresponding pair of pinions, and guides secured beneath the car intermediate of the doors for supporting said shaft and directing the same upwardly when rotated to close the doors.

9. In a freight car, the combination with a downwardly swinging door in the bottom thereof, of a longitudinal shaft, a pinion fixed upon said shaft, a rack bar fixed upon the under surface of said door with which said pinion meshes, guides secured beneath the car for supporting said shaft and directing the same upwardly when rotated to close said door, an upwardly inclined ratchet bar fixed beneath said car adjacent one end thereof, a pawl loosely carried by said shaft engaging the teeth of said ratchet bar, and a ratchet lever for intermittently oscillating said shaft.

10. In a freight car, the combination with the roof thereof, of a longitudinal sliding door closing an opening in the roof, longitudinal guides located on the roof at each side of the door openings, projections on the door engaging said guides, and short guides spaced apart distances less than the length of the door and located in alinement with said longitudinal guides.

11. In a freight car, the combination with the roof thereof, of doors closing openings through the roof at each side of its longitudinal center, transverse roof beams supporting the roof at each side of the door openings, and a transverse brace extending beneath the roof intermediate of the door openings.

12. In a freight car, the combination with the roof thereof, of doors closing openings through the roof at each side of its longitudinal center, longitudinal guides for said doors, projections on the edges of said doors engaging said guides, hangers depending from the central longitudinal guides, and a transverse brace extending beneath the roof intermediate of the door openings and supported at its ends by said hangers.

13. In a car, a side truss comprising as its compression member the roof beam and as its tension member the central portion of the side sill, and tie rods connecting the central portion of the side sill to the ends of the roof beam.

SPENCER OTIS.
